(57) **CLAIM**

The ornamental design for a swimming cap, as shown and described.

DESCRIPTION

FIG. 1 is a perspective view of the swimming cap according to the invention;

FIG. 2 is a front view of the invention;

FIG. 3 is a side view of the invention; and,

FIG. 4 is a rear view of the invention.

The broken lines in the drawings illustrate environmental matter and form no part of the claimed design.
